(57) **CLAIM**

The ornamental design for patient ankle support cushions, as shown and described.

DESCRIPTION

FIG. 1 is a perspective view of patient ankle support cushions incorporating the design.

FIG. 2 is a top view thereof.

FIG. 3 is a bottom view thereof.

FIG. 4 is a right-side view thereof.

FIG. 5 is a left-side view thereof.

FIG. 6 is a front view thereof; and,

FIG. 7 is a back view thereof.

The broken lines shown in the drawings illustrate portions of the patient ankle support cushions that form no part of the claimed design.

1 Claim, 6 Drawing Sheets
